UNITED STATES PATENT OFFICE.

CONRAD BAUMGARTNER, OF SCHENECTADY, NEW YORK, ASSIGNOR TO GENERAL ELECTRIC COMPANY, A CORPORATION OF NEW YORK.

MEANS FOR CORRUGATING SHEET METAL.

1,098,144.

Specification of Letters Patent.

Patented May 26, 1914.

Application filed January 30, 1908. Serial No. 413,372.

To all whom it may concern:

Be it known that I, CONRAD BAUMGARTNER, a citizen of the United States, residing at Schenectady, county of Schenectady, State 5 of New York, have invented certain new and useful Improvements in Means for Corrugating Sheet Metal, of which the following is a specification.

This invention relates to means for corrugating heavy sheet iron or steel, for the purpose of forming the walls of transformer tanks. At the present time large transformers are immersed in oil contained in tanks of metal, the walls of which are corrugated or fluted to afford as large a surface as possible to promote the radiation of the heat absorbed by the oil. In attempting to make such tanks from sheet iron or steel, it has been found difficult to make the corrugations very deep, owing to the impossibility of using toothed corrugating rolls with deep closely spaced teeth. If deep teeth are used, they must be spaced widely apart in order to enable them to enter and clear each other 15 in the revolution of the rolls. But if spaced widely apart the resulting corrugations are unsuitable for a transformer tank, not giving enough surface for proper radiation. The problem, therefore, is to produce deep 20 closely spaced corrugations without unduly stretching or breaking the sheet metal. It is evident that this cannot be successfully done with dies which corrugate the whole sheet at once, and if the corrugations are 25 to be made one by one, a machine using rolls is much simpler to operate.

My improved method consists in rolling corrugations by means of toothed rolls having widely spaced teeth which will clear 30 each other without trouble, then squeezing the corrugations together, finally bringing them all to a standard shape and regularity of spacing, trimming off the edges of the sheet, and flanging it for welding to an adjacent sheet. This method is carried out by any suitable mechanism, such for instance as that illustrated in the accompanying drawings, in which—

Figure 1 is a front elevation of the crimping machine for fluting or corrugating the sheets and squeezing the corrugations closer together; Fig. 2 is an end elevation of the same; Fig. 3 is a vertical cross-section of the same; Fig. 4 is an elevation of a portion of

the friction clutch; Fig. 5 is a longitudinal 55 section of the clutch; Fig. 6 is a sectional detail of the mechanism for lifting and lowering the tweezer jaws; Fig. 7 is a similar view of the mechanism for operating said jaws; Fig. 8 is an elevation of the boxes 60 for the shafts and the means for adjusting them; Fig. 9 is a front elevation of the finishing machine; Fig. 10 is a detail showing the cutting device; Fig. 11 shows the adjacent edges of two corrugated plates; Fig. 65 12 is an end elevation of the finishing machine; Fig. 13 is a sectional elevation of the finishing rolls; and Fig. 14 is a perspective view of the feeding table of this machine.

The first steps of my method may be 70 carried out by the mechanism shown in Figs. 1 to 8 of the drawings. This machine, which I term the crimping machine, comprises two end frames or uprights 1 2, joined at the top by a beam or stay 3 and lower down by the 75 front and rear girders 4 5. To the lower portions of the end uprights there are bolted the brackets 6 7, respectively, provided with journal bearings for the two parallel shafts 8 9 which extend across the machine. The 80 upper portions of the uprights are vertically slotted to receive the blocks 10 11, one above the other, containing journal bearings for two shafts on which are mounted the corrugating or crimping rolls 12 13, which have 85 widely spaced deep teeth. On the ends of these shafts are the meshing pinions 14 15. The shaft 16 of the lower roller 13 is driven by a train of spur gears and pinions 17 18 19 20, the latter being keyed on the shaft 9. 90 A spur gear 21 is loosely sleeved on said shaft and is suitably driven, as by the electric motor 22. Said gear is adjacent to a disk 23 whose hub is free to slide lengthwise of the shaft 9, preferably by being splined 95 upon the hub of one of the pinions 20. In the hub of the disk is a circumferential groove 24 to receive pins carried by the arms of a fork 25 on the upper end of a lever 26 which is pivoted at its lower end to a block 100 27. A shaft 28 extends across the end of the machine and is provided with one or more operating handles 29. The shaft carries an arm 30 which is connected with the lever 26 by a link 31, the arm and the link forming a 105 toggle which, when straightened out, acts to force the disk 23 toward the gear 21. The latter has a conical recess into which

conical projections 23 on the disk can enter, thereby frictionally clutching the disk to the gear and causing the rolls to be rotated.

The lower journal box 11 for the lower roll rests solidly on the bottom of the upright slot in the end upright. Between this and the upper journal box 10 there is a shim 32, as shown in Fig. 8. The upper surface of this shim and the lower surface 10 of the box 10 are inclined, so that when said shim is moved lengthwise by the adjusting screws 33 and 34 the distance between the centers of the rolls 12 13 is altered, to insure the proper working of said rolls. After adjustment, the heavy set screw or clamping screw 35, abutting between the block 10 and the stay 3 can be tightened to hold the boxes rigidly in place.

In order to prevent tearing or injuring 20 the sheet metal, it is necessary that the pitch of the teeth on the crimping rolls be such that only one tooth will be in mesh at any one time, as clearly shown in Fig. 3. The effect of this construction is to impart to 25 the sheet metal a series of broad shallow corrugations; whereas, in transformer tanks it is desirable to make the corrugations deep and narrow, as explained above. The next step of my method, therefore, is to squeeze 30 together the wide corrugations. This may be accomplished by any suitable device, but I prefer to effect it by a pair of tweezer jaws 36 37 mounted in the frame of the crimping machine and driven from the shaft 35 8 by means of cams 38 39 thereon. The upper edges of these jaws are rounded to fit into the corrugations of the sheet, and the jaws are pivoted or hinged together at 40 on an axis transverse to the machine. 40 The jaw 37 is arranged to slide up and down on slides or ribs 41 projecting from the brackets 42 secured to the uprights 1 2. In order to move the jaws, so as to carry them up into adjacent corrugations as soon 45 as a new corrugation passes beyond the rolls, the cams 39 lift pivoted rocker arms 43 which are connected by links 44 with ears on the jaw 37. A plate 45 lies above the corrugated sheet of metal, and prevents it 50 from being raised when the upper edges of the jaws are pushed into the corrugations.

The cams 39 on the shaft 8 are so arranged that as soon as the tweezer jaws have been raised said cams force back the lower ends 55 of levers 46, fulcrumed at 47, and connected at their upper ends by adjustable links 48 with the lower end of the tweezer jaw 36. This action of the cams 39 brings the upper edge of the jaw 36 toward the jaw 37 and 60 squeezes the corrugation lying between them. The plate 49 on which the sheet rests has fingers which project through openings 50 in the tweezer jaws and serve to strip the sheet from said jaws when they move downward. By means, therefore, of these tweezer

jaws, the relatively wide shallow corrugations formed by the rolls are compressed together into relatively narrow deep ones.

The next step in my method consists in evening all the corrugations so that they 70 will have a uniform shape, trimming the edges of the sheet, and properly flanging or otherwise shaping said edges to enable two sheets to be readily joined together. The devices for effecting this are shown in 75 Figs. 9, 10, 12, 13 and 14, and consist of a gang of rollers, preferably two pairs, circumferentially grooved to permit the corrugations to pass through them endwise. The first pair of rollers is composed of 80 preferably a plurality of disks 51 placed in juxtaposition on a suitable shaft 52 and having their edges thinned and rounded to fit into the corrugations of the sheet. These rollers even up all the corrugations and give 85 them a uniform shape. At each end of the rollers is a pair of cutting disks 53 54, which trim the edges of the sheet. Owing to the larger diameter of the cutter 54, the material will be grasped by the cutters an 90 instant before it is caught by the disks 51. The other roller shafts 55 carry a few separated disks 56 which serve as guides for the sheet. These shafts also carry at their 95 ends special disks 57 58 which give to the edges of the sheet a flange or other shape which makes it convenient to join adjacent by welding. The preferred form of the flange is shown in Fig. 11, at 59. On the feed table 60 there are stationary ribs 61 100 serving as guides to insure a true starting of the corrugated sheet through the rollers. This is highly necessary, because if the rollers should grasp one edge of the sheet before the other, the sheet would be badly 105 twisted and distorted.

The roller shafts are all driven synchronously by any suitable power, such as the motor 62, actuating the trains of gears shown.

What I claim as new and desire to secure by Letters Patent of the United States, is,—

1. In a machine for corrugating sheet metal, the combination with crimping rolls having widely spaced teeth, of simultaneously operating tweezer jaws adjacent thereto for squeezing the corrugations together. 115
2. In a machine for corrugating sheet metal, the combination with crimping rolls having widely spaced teeth, of simultaneously operating tweezer jaws adjacent thereto for squeezing the corrugations together, and means for raising and lowering said jaws. 120
3. In a machine for corrugating sheet metal, the combination with crimping rolls having widely spaced teeth, of simultaneously operating tweezer jaws adjacent thereto for squeezing the corrugations together, means for raising and lowering said jaws, 125

and means for opening and closing said jaws in synchronism with their up and down movements.

4. The combination with rolls for forming wide shallow corrugations in sheet metal, of tweezer jaws adjacent to said rolls, rotary cams for raising and lowering said jaws, and gear connection between said cams and said rolls whereby the jaws are caused

to operate simultaneously with the rolls to produce deep closely spaced corrugations in the sheet metal.

In witness whereof, I have hereunto set my hand this 28th day of January, 1908.

CONRAD BAUMGARTNER.
